UNITED STATES PATENT OFFICE

2,365,975

CUTTER CHAIN

Leon E. Simmons, Claremont, N. H., assignor to
 Sullivan Machinery Company, a corporation of
 Massachusetts

Application June 12, 1944, Serial No. 539,806

9 Claims. (Cl. 262—33)

This invention relates to cutter chains and more particularly to an improved hinge pin lock and bit stop for a mining machine cutter chain.

An object of the present invention is to provide an improved cutter chain. Another object is to provide an improved hinge pin connection between the chain blocks and connecting links of a cutter chain whereby wear is concentrated on the relatively inexpensive connecting links. Yet another object is to provide an improved cutter chain having an improved combined hinge pin lock and bit stop. A further object is to provide an improved hinge pin lock for holding the hinge pin against rotation with respect to the chain block. Still another object is to provide an improved bit stop for the cutter bit received in the socket of the chain block. A further object is to provide an improved bit stop which is formed integral with a hinge pin lock. Other objects and advantages of the invention will, however, hereinafter more fully appear.

In the accompanying drawing there is shown for purposes of illustration one form which the invention may assume in practice.

In this drawing:

Fig. 1 is a side elevational view of a section of a cutter chain in which an illustrative form of the invention is incorporated.

Fig. 2 is a cross sectional view taken substantially on the lines 2—2 of Fig. 1, showing the block lug and cutter bit in front elevation.

Fig. 3 is a view in longitudinal vertical section taken substantially on line 3—3 of Fig. 2.

Fig. 4 is a view in substantial horizontal section taken on the lines 4—4 of Fig. 1.

Fig. 5 is a detail cross sectional view taken on line 5—5 of Fig. 1.

Fig. 6 is an enlarged detail view of a combined pin lock and bit stop.

Fig. 7 is an enlarged perspective view of one of the hinge pins.

In the illustrative embodiment of the invention, there is shown a mining machine cutter chain including a chain block 1 pivotally connected at 2 to connecting links 3. The chain block has a lateral lug 4 provided with a socket 5 for the insertion of a standard shanked cutter bit 6. The cutter bit is secured in cutting position in the block socket by a set screw 7 threaded within an opening 8 in the block lug. The chain block has parallel side portions 9, 9 provided with lateral gibs 10 adapted for reception in the guideway of a conventional mining machine cutter bar. The connecting links project inwardly between the side portions 9 of the

block; and, provided between the adjacent ends of the links within the block, is a sprocket tooth receiving space 11. The bit receiving socket 5 enters at its bottom the tooth-space 11 between the link-ends and, if no stop were provided, the bit shank would be free to drop down too far into the tooth-space 11 and so to interfere with proper engagement of the sprocket tooth with the links. The side portions 9 of the chain block have lateral apertures 12 communicating with the tooth-space 11 to permit the discharge of dirt or cuttings from the tooth-space. The cutter chain structure above described is conventional and well known to those skilled in the art.

The pivotal connections 2 between the blocks and links include hinge pins 13 arranged in aligned transverse bores 14 and 15 in the blocks and links respectively. The ends of the pins are substantially flush with the outer sides of the block portions 9, as shown in Fig. 2, and the pins have longitudinal openings or bores 16 extending centrally therethrough. Notches or grooves 17 in the ends of the pins enter the central bores 16 and extend laterally through a side of the pins into registry with slots or grooves 18 in the side portions 9 of the block. The grooves 18 enter the block apertures 12, and are relatively upwardly inclined in the manner clearly shown in Fig. 1. The combined pin locks and bit stops 19 are each generally designated 19 and may be formed in various manners and herein consist of a piece of deformable metal preferably in the form of wire bendable into the desired shape. Prior to bending into operative pin locking position on the block, the lock and stop is of generally U-shape, as shown in Fig. 6, with one leg 20 of the U somewhat longer than the other leg 21. The lock and stop is placed in position on the block by inserting the shorter leg 21 in the central bore 16 in the pin and inserting the longer leg 20 through the block aperture 12 across the block above the tooth-space 11, and thereafter the longer leg is bent laterally into the position indicated in dotted lines in Fig. 6 in parallelism with the base 22 of the U. When the ends of the legs 20 are bent properly into place, as shown in Fig. 4, they are disposed in the registering grooves 18 and 17 in the block and pin with the base 22 of each U disposed in the grooves 18 and 17 at the other side of the block so that the hinge pins 13 are rigidly locked against rotation with respect to the block. And the U-portions which extend through the block apertures 12 and traverse the block just above the tooth-space 11 and beneath the bit-receiving

socket 5, provide stops for the shank of the cutter bit 6 to prevent the insertion of the bit shank into the tooth-space 11. The hinge pins may be readily disassembled simply by bending the longer legs 20 of the U into the full line position shown in Fig. 6 with the U-legs 20 and 21 in parallel relation, so that the U-shaped members may be withdrawn laterally from the block, and, in this same manner, the U-shaped members may be readily replaced. The bit stop portions of the U-members, passing through the lateral apertures 12 of the block, do not obstruct the openings sufficiently to prevent the free discharge of dirt and cuttings from the tooth-space 11.

As a result of this invention, an improved cutter chain is provided wherein common elements serve to lock the hinge pins to the block and to provide a stop for the cutter bit in the block socket. By the provision of the improved combined pin lock and bit stop, a relatively simple and inexpensive structure results. The improved pin lock and bit stop may be readily placed in position and may be incorporated in a chain block of a standard design with a minimum of change. These and other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a cutter chain, a chain block, a connecting link, a hinge element for pivotally connecting said block and link, said block having a socket for receiving a cutter bit, and detachable means for locking said hinge element against rotation relative to said block and including a portion extending beneath the block socket to provide a bit stop.

2. In a cutter chain, a chain block, a connecting link, a hinge element for pivotally connecting said block and link, said block having a socket for receiving a cutter bit, and a detachable member engaging said hinge element and block for locking said hinge element against rotation relative to said block, said member having a portion extending into a position with respect to the block socket to provide a stop for a bit in said socket.

3. In a cutter chain, a chain block, a connecting link, a hinge element for pivotally connecting said link to said block, said block having a socket for receiving a cutter bit, and a combined lock and stop means for locking said hinge element against rotation relative to said block and for providing a stop for a bit in said block socket.

4. In a cutter chain, a chain block having a bit-receiving socket, connecting links pivotally connected to said block, the pivotal connections between the links and said block including hinge pins, and a combined pin lock and bit stop means for locking said pins against rotation relative to said block and including portions extending across the block between adjacent link-ends and

beneath said bit-receiving socket to provide a bit stop.

5. In a cutter chain, a chain block having a bit-receiving socket, connecting links pivotally connected to the opposite ends of said block, the inner adjacent ends of said links being spaced apart to provide a space within the block beneath said bit-receiving socket and the pivotal connections between the links and said block including hinge elements, and means associated with each of said hinge elements for locking the latter against rotation relative to said block, said locking means having portions traversing the block in said block space beneath said bit-receiving socket to provide a stop for a bit in said socket.

6. In a cutter chain, a chain block having a bit-receiving socket, connecting links pivotally connected to the opposite ends of said block, the inner adjacent ends of said links being spaced apart to provide a space in said block beneath said bit-receiving socket, said block having lateral openings connecting the block space with the exterior of the block and the pivotal connections between the links and said block including hinge elements, and locking means for each of said hinge elements for locking the latter against rotation relative to said block, said locking means having portions extending across the block through said openings and across said block space beneath the bit-receiving socket to provide a stop for a bit in said socket.

7. In a cutter chain, a chain block having a sprocket-tooth-receiving space provided at the bottom portion thereof, and a bit-receiving socket entering said space at its inner end, a connecting link, a hinge element for pivotally connecting said link to said block, and means engaging said hinge element and block for locking said element against rotation relative to said block, said locking means having a portion traversing the block above the sprocket-tooth-receiving space and beneath said bit-receiving socket to provide a stop for a bit in said socket.

8. In a cutter chain, a chain block having a bit-receiving socket, a connecting link, a hinge pin for pivotally connecting said link and said block, said hinge pin having a bore extending longitudinally therethrough, and a member extending through said hinge pin bore and engaging said block for locking said hinge pin against rotation relative to said block, said member having a portion traversing said block beneath the block socket to provide a stop for a bit in said socket.

9. In a cutter chain, a chain block having a bit-receiving socket, a connecting link, a hinge pin for pivotally connecting said block and said link, said hinge pin having a bore extending longitudinally therethrough, and said block having an opening extending thereacross beneath said bit-receiving socket, said hinge pin and said block having registering grooves, and a combined pin lock and bit stop comprising a member having a portion extending into said pin bore and another portion seated in said registering grooves, said member having another portion extending across the block through the block opening beneath said bit-receiving socket to provide a stop for a bit in said socket.

LEON E. SIMMONS.
